UNITED STATES PATENT OFFICE.

JOHN WHITE, OF EDINBURGH, SCOTLAND.

APPARATUS FOR STRAINING PAPER-PULP, &c.

SPECIFICATION forming part of Letters Patent No. 728,346, dated May 19, 1903.

Application filed January 6, 1902. Serial No. 88,652. (No model.)

To all whom it may concern:

Be it known that I, JOHN WHITE, a citizen of the United Kingdom of Great Britain and Ireland, residing at Leith Walk Foundry, 5 Edinburgh, Scotland, have invented certain new and useful Improvements in Apparatus for Straining Paper-Pulp and Like Material, (for which application for patent has been made in Great Britain, No. 24,381, dated November 30, 1901,) of which the following is a specification.

In a well-known type of apparatus for straining paper-pulp and described in the British patent of Roeckner, No. 7,932 of 1885, the pulp contained within a stationary vat is caused to pass through the perforated shell or drum of a cylindrical, prismatic, or similar vessel arranged to oscillate upon a central concentric shaft or axis, the strained pulp 20 passing off through a flexible outlet connection to a separate box outside of the vat. Within the drum radial division-plates, partitions, or fans are fixed, and as the drum oscillates to and fro these produce a pulsating 25 action or alternate suction and expulsion of the pulp passing through the perforations or slits of the drum.

My invention has for its object, besides generally improving the construction of pulpary straining apparatus of this type, to obtain 30 greater area of strainer-plates in any given size of vat and render the strainer more effective, while by increasing the number of outlets to two or more, and thus decreasing 35 their diameter, so improving the flexible outlet connections from the oscillating strainer as to lessen the twisting action, and thus reduce wear and tear.

The invention is illustrated by the accompanying drawings, in which—

Figure 1 is a longitudinal sectional elevation. Fig. 2 is a cross-section, and Fig. 3 a part plan, of the improved strainer.

As shown by the drawings, the improved 45 strainer is composed of a number of strainer drums, cylinders, or elongated tubular vessels *a a*, secured to and alongside a central rocking shaft *b*, with their axes parallel or approximately parallel to the axis of oscillation 50 instead of being, as heretofore, concentric therewith, the shaft *b* being carried in bear-

ings at the ends of a trough-like vat *c*, within which the strainer oscillates immersed in the pulp which is fed into it through one end of the vat. In the arrangement illustrated 55 two drums or straining vessels *a a* are secured to the oscillating shaft *b* within the vat *c*, the straining vessels being each by preference of the form of partially-flattened tubes or barrels or of double-convex or lozenge shape in 60 cross-section, with their major axes vertical, so as to provide as large a surface as possible within a restricted width of vat. The drums or vessels *a a* are divided by partition-plates *a'*, preferably extending vertically across the 65 axis, so as to form cells or compartments in each drum *a*, and these division-plates may be flat or corrugated or straight or inclined. The ends of the straining vessels are formed by plates *a''*, secured to the oscillating shaft 70 *b*, and on these plates may be formed flanges *a'''*, to which the strainer-plates *d*, constituting the shell of each drum or vessel, may be bolted or held by clip-plates *f*, or light skeleton frames may be secured upon the shaft 75 and the strainer-plates *d* fixed thereto. At their meeting edges at top and bottom the strainer-plates *d* may be conveniently bolted together, with the vertical partition-plates between them, the longitudinal ends being held 80 by clip-plates.

Each drum or straining vessel *a* is connected by a straight flexible tube *h* to the end of the vat leading into a delivery-box *i*, common to each outlet. These flexible tubes may 85 be placed in any position below the axis of oscillation.

The oscillation of the shaft *b* may be conveniently effected by a crank or lever arm *j*, fixed on it and connected to an eccentric or 90 like device on a rotating shaft.

Having now described the invention, what I claim, and desire to secure by Letters Patent, is—

1. A pulp-strainer composed of a plurality 95 of strainer-drums or elongated tubular vessels arranged within a vat or trough, and a central rocking shaft to and alongside which said drums are secured with their axes parallel to the axis of said shaft, substantially 100 as described.

2. In a pulp-strainer the combination with

vat and a rock-shaft extending therethrough, of two drums or flattened tubular vessels secured one to either side of and parallel to said shaft, the shells of said drums being composed of strainer-plates and flexible tubes connecting their ends and a delivery-box without the vat, substantially as described.

In witness whereof I have hereunto set my hand in presence of two witnesses.

JOHN WHITE.
